UNITED STATES PATENT OFFICE.

WASHINGTON BAKER VANDERLIP, OF SAN DIEGO, CALIFORNIA, ASSIGNOR OF THIRTY-FIVE ONE HUNDREDTHS TO ERNEST SCHERNIKOW, OF NEW YORK, N. Y.

ORE-CONCENTRATOR.

1,263,968.

Specification of Letters Patent. Patented Apr. 23, 1918.

Application filed September 4, 1917. Serial No. 189,632.

To all whom it may concern:

Be it known that I, WASHINGTON BAKER VANDERLIP, a citizen of the United States, residing at San Diego, in the county of San Diego and State of California, have invented certain new and useful Improvements in Ore-Concentrators; and I do hereby declare the following to be a full, clear, and exact description of the invention, such 10 as will enable others skilled in the art to which it appertains to make and use the same.

My present invention relates to improvements in concentrators for ores and the like, 15 preferably, though not necessarily, of the batea or centripetal type wherein a circular vanning movement is imparted to the concentrating table, and wherein the discharge of the heavy concentrates is accelerated by 20 a suitable revolving worm screw, and wherein this worm screw may be driven at a variable speed to conform to the desired rate of delivery of the concentrates; and in which the separation of the concentrates from the 25 gangue is accelerated by a series of radial baffle plates mounted in the bottom of the pan, and whereby also the radius of the circular movement of the pan may be adjusted within limits, so as to impart a variable 30 lateral throw to the pan.

My invention will be more clearly understood after reference to the accompanying drawings, which show the embodiment of the invention, and in which like parts are 35 indicated by similar reference symbols throughout the several views.

Figure 1 is a plan view of the top of the pan, part of one edge of the pan being broken away in order to show details on a 40 larger scale, the arrangement for feeding the ore to the pan being omitted;

Fig. 2 shows a central vertical section through the main body of the pan along the line 2—2 of Fig. 1, and also through the 45 device for feeding the ore to the pan, parts of the mechanism for moving the pan being shown in section and parts in elevation, and the mechanism for driving the worm for withdrawing the concentrates from the pan 50 being shown in elevation;

Fig. 3 shows a plan view of the cone drive for rotating the delivery screw, whereby the speed of movement may be quickly varied;

Fig. 4 is a side elevation of the device shown in Fig. 3, as seen from the bottom of Fig. 3;

Fig. 5 is an end view as seen from the right of Fig. 3; and

Fig. 6 shows the sliding connection between parts of the broken shaft used in 60 driving the worm conveyer.

1 represents the outer wall of the launder which is attached to and moves with the pan 2, which is in the form of an inverted frustum of a cone, having the central opening 65 3. Surrounding the exterior of this conical portion 2 of the pan is a launder 4 for the gangue, in the form of a circular trough which is broad and shallow as at 5, and narrow and deep as at 6, the narrow and deep 70 portions terminating in outlets 7 which open into any suitable troughs or other conveyers, not shown, for carrying off the gangue.

Mounted in the interior of the conical portion of the pan are a series of radial 75 baffle plates, preferably of different lengths and staggered, as shown at 9 and 10. These baffle plates are secured to the bottom of the pan in any convenient way, as by the flanges and bolts shown in Fig. 1, and between these 80

flanges, and next to the bottom of the pan, the baffle plates are cut away to form elongated openings 11, see Fig. 2. These baffle plates preferably all terminate at substantially the same distance from the outer edge 85 of the cone part of the pan, but the inner ends of the baffle plates 9 project farther toward the opening 3 than do the short baffle plates 10.

Mounted beneath the opening 3 is a funnel 12, terminating in the cylinder 13, see Fig. 2. In this cylinder is mounted the worm conveyer 14, mounted on the shaft 15 which is journaled at one end in the bottom of the cylinder 13, and at the other end in 95 the bearing 17 supported by the bracket 16, secured to the inside of the bottom of the pan.

This cylinder 13 has a delivery opening 13^a, through which the concentrates fed by 100

the conveyer 14 pass. The pan is given a vanning movement, as will be hereinafter described, and to impart rotary motion to the shaft 15 I provide a broken shaft, consisting of the universal joint 18, the shaft segment 19, splined as at 19^a to slide in the sleeve 20, connected by the universal joint 20^a to the segment 21, which segment carries the worm gear 22 meshing with the worm 23 on the shaft 24, which shaft carries the friction cone 25. Opposite this friction cone, and reversely disposed, is a similar friction cone 26 mounted on the shaft 27, carrying the beveled gear 28 meshing with 15 the beveled gear 52 on the main drive shaft 51.

The shaft 27 is mounted in bearings 29 carried by the supports 30. The shaft 24 is journaled in sleeves 31 carried by the 20 stems 32, adjustably mounted in the blocks 34. Between the bearings 31 and blocks 34 I provide the springs 33, which tend to press the cone 25 toward the cone 26. These bearings 34 are carried by the frame 35. The 25 stems 32 may be adjusted by means of the adjusting screw bolts 36.

Passing between the two cones is a belt or collar 37, of leather, reinforced rubber, or other suitable material, which passes 30 through the shifter 38 and feeding nuts 39 engaging the screw rod 40, having a handle 41. The shifter slides freely on the rod 42, and may be moved backward or forward along said rod by turning the handle 41. The rod 42 is secured at its opposite ends to the brackets 43 and 44 carried by the frame 35, and the rod 40 is journaled in said brackets.

It will be evident that by moving the 40 collar 37 to the right or left between the two friction cones that the angular velocity of the cone 25, relative to that of the cone 26, may be increased or decreased as desired.

In order to throw the cone 25 entirely out 45 of engagement when desired, I provide a grooved collar 45, fast to the cone 25 and engaging one end of the clutch lever 46, the other end 47 of which may be operated by hand when desired.

50 The main drive shaft 51 is driven at a variable speed in any convenient way, as by means of the differential pulleys 50, shown in dotted lines in Fig. 1. This shaft 51 carries at each end beveled pinions 52^a engaging the beveled pinions 53, mounted on the shaft 54 carrying the eccentrics 55. The opposite pair of eccentrics 55 are driven by the beveled gear 56 carried by the shaft 27, which beveled gear meshes with the beveled gear 57 on the shaft 51^a, at the two ends of which shaft are the beveled gears 52^b which mesh with the beveled gears 53^a, and drive the corresponding shaft 54 and eccentrics 55. These beveled gears are all

arranged so that the various shafts 54 and 65 the various eccentrics shall all have the same angular velocity, and in order to get the proper direction of movement of the eccentrics on opposite sides of the pan, the beveled gear 53 should be reversely disposed 70 to the beveled gear 53^a.

The eccentrics 55 may be preferably of the well known type known as adjustable eccentrics, whose eccentricity may be varied within limits, as desired, so that the throw of 75 the eccentrics may be increased or decreased as desired. These eccentrics engage the cylindrical bearings 58 in the housing 59, see Fig. 2. Each eccentric 55 is provided with a stem 60 concentric with the bearing 58, 80 and surrounding this stem are the end friction bearings 61.

Lubricant may be supplied through a suitable lubricator 62.

The housings 59 are rigidly attached to 85 the under frame 63 carrying the pan. The shafts 54 supporting the pan are journaled in hollow columns 64, secured together by suitable tie rods 65.

The ore for treatment is preferably provided to the pan by a feeding device which will evenly distribute the feed of the wet ore to the pan. Such an apparatus is shown in section in Fig. 2, in which 70 represents supporting beams secured to any suitable framework, not shown, which beams support the trough or tank 71, provided with an opening 72 above the cylinder 73, which is supported from the tank 71 beneath which is suspended, as by means of the link 74, a 95 cylindrical metal receptacle 75, beneath which is suspended an inverted cup-shaped receptacle 76, having the flanged annular trough 77, which is substantially concentric with the axis of the pan. 100

105 It will be obvious that if the ore in the usual semi-liquid state be supplied to the tank 71 it will flow through the opening 72 and into the receptacle 75, and overflowing around the sides of this receptacle it will 110 flow into the annular trough 77, and from which it will flow in a substantially uniform sheet into the pan at a suitable distance from the opening 3 therein.

The operation of the device is as follows:—

Suppose all the parts of the machine to be in operation and the pan to be given the vanning motion imparted to it by the eccentrics 55, the ore in the wet condition as it 120 comes from the stamp mills is fed into the tank 71, flowing down into the receptacle 75, and it flows over the upper sides of said receptacle and into the annular trough 77, whence it is distributed in an even sheet onto 125 the top of the ore already in the pan. The heavier concentrates are gradually shaken to the bottom of the pan under the action of

the vanning motion referred to, and sliding down the inclined bottom of the pan pass into the funnel 12, and would tend to cake there like so much mud if placed in a funnel, were they not positively forced downward by the worm conveyer 14. Water and lighter gangue particles tend to rise to the top of the ore in the pan and are thrown out by centrifugal force and flow into the trough 4, whence they escape through the outlet 7 and are carried off as tailings.

10 The ore and water mixed should be kept in the pan at a height of an inch or more above the top of the baffle plates 9 and 10, and their function is to agitate and slap the ore, causing the lighter particles of gangue to be thrown toward the delivery edge of the pan. Without these baffle plates the ore in the deepest part of the pan would stagnate 20 and settle to the bottom.

15 The open spaces 11 at the bottom of the baffle plates are provided for the reason that when the concentrates sink out of the agitated pulp to the floor of the pan they do not travel in a straight line downward to the center well, but approach it in concentric lines, this motion being accomplished by the throw of the eccentrics; and if the particles of concentrate were not allowed to 25 pass underneath the baffle plates they would pile and bank up against the lower side. For a similar reason the baffle plates are brought to within one inch of the water surface. For this reason the larger particles 30 of waste material, such as quartz, rise to the top of the pulp in the same manner that you shake up a bushel of potatoes and the large potatoes come to the top.

35 If the baffle plates extended to the surface 40 of the water by reason of the throw of the pan, the lighter particles of ore and gangue would bank up against the sides of the plates; but with this invention it allows them to approach the edge of the pan in concentric lines opposite to the direction of 45 the concentrates below, and thus escape over the side into the discharge launder.

It will be noted that the flow of the 50 concentrates will be toward the center, but in 55 a curved line indicated by the arrows "A" in Fig. 1, while the flow of the waste material will be toward the periphery of the pan and in reverse direction, as indicated by the arrows "B" in Fig. 1, while the circular movement of the pan will be in the 55 direction of the arrow C.

The cylinder 13 is substantially vertical, and has its discharge opening below the worm 14; and the convolutions of the worm 60 being close spaced, and the worm being slowly turned, a positive but retarded discharge of concentrates is secured, and a suitable depth of material under treatment is maintained in the pan.

Since certain ores require much longer 65 treatment in the pan for their proper concentration, it is essential that the worm conveyer 14 should be readily adjustable, and by the arrangement herein shown a wide range of adjustability is secured. 70

With the arrangement herein shown in actual practice, the drive enables the speed imparted to the screw to be varied from one revolution per minute to sixteen revolutions per minute, thus causing the apparatus to 75 be adjusted to deliver the proper proportion of concentrates, which is very much with certain ores and very small with others. For instance, a certain run of ore may yield a high percentage, such as 5% of concentrate, 80 and another one the same day may yield as low as $\frac{1}{2}\%$ to 1% of concentrate, and instead of being obliged to mix the ores at great expense in the bins, it is sufficient for 85 the man at the bins to telephone to the operator at the concentrators the quality of ores that he may expect, and have him set his cone drive accordingly, thus varying the relative speed of the screw and consequently varying the quantity of the material ejected. 90

By adjusting the eccentrics the movement of the pan may be varied within limits as desired.

The invention is especially applicable to galena or other sulfid ores, but it may be 95 used to secure concentrates from the various ores to which a vanning or gyratory motion is imparted.

It will be obvious that various modifications might be made in the herein described 100 apparatus, and in the construction, combination and arrangement of parts which could be used without departing from the spirit of my invention.

Having thus described my invention, what 105 I claim and desire to secure by Letters Patent of the United States is:—

1. Apparatus for concentrating ores, comprising a pan provided with a peripheral discharge and having a bottom in the form 110 of an inverted truncated cone perforated at the bottom, a substantially vertical cylinder mounted beneath the opening in the center of said cone and having a discharge opening, a worm conveyer having close convolutions mounted in said cylinder, means for vanning said pan, and means for rotating said worm conveyer while said pan is in motion, substantially as described. 115

2. Apparatus for concentrating ores, comprising a pan provided with a peripheral discharge and having a bottom in the form of an inverted truncated cone perforated at the bottom, a substantially vertical cylinder mounted beneath the opening in the center of 120 said cone and having a discharge opening, a worm conveyer having close convolutions mounted in said cylinder, means for van-

ning said pan, and adjustable means for rotating said worm conveyer at a variable speed while said pan is in motion, substantially as described.

5 3. Apparatus for concentrating ores, comprising a pan provided with a peripheral overflow and a bottom in the form of an inverted truncated cone perforated at the bottom, a substantially vertical cylinder 10 mounted below the opening in said pan and having a discharge opening, a worm conveyer having close convolutions mounted in said cylinder, the said cylinder being provided with a discharge opening below said 15 worm, a flexible shaft for rotating said worm conveyer, means for vanning said pan, and means for rotating said flexible shaft while said pan is in motion, substantially as described.

20 4. Apparatus for concentrating ores, comprising a pan provided with a peripheral overflow and a bottom in the form of an inverted truncated cone perforated at the bottom, a substantially vertical cylinder 25 mounted below the opening in said pan and having a discharge opening, a worm conveyer having close convolutions mounted in said cylinder, the said cylinder being provided with a discharge opening below said 30 worm, a flexible shaft for rotating said worm conveyer, means for vanning said pan, and adjustable means for rotating said flexible shaft at a variable speed while said pan is in motion, substantially as described.

35 5. Apparatus for concentrating ores, comprising a pan provided with a peripheral overflow and having a bottom in the form of an inverted truncated cone perforated at the bottom, a series of radially disposed 40 baffle plates mounted in said pan, a funnel mounted beneath the opening in the center of said cone, a cylinder below said funnel, a worm conveyer mounted in said cylinder, means for vanning said pan, and 45 means for simultaneously rotating said worm conveyer, substantially as described.

6. Apparatus for concentrating ores, comprising a pan provided with a peripheral overflow and having a bottom in the form 50 of an inverted truncated cone perforated at the bottom, a series of radially disposed baffle plates mounted in said pan, said baffle plates having elongated slots there- 55 through adjacent to the bottom of said pan, and said baffle plates being of less depth than the corresponding portion of the pan, a funnel mounted beneath the opening in the center of said cone, a cylinder below said funnel, a worm conveyer mounted in said cylinder, means for vanning said pan, and means for simultaneously rotating said worm conveyer, substantially as described.

7. Apparatus for concentrating ores, comprising a pan provided with a peripheral

overflow and having a bottom in the form of an inverted truncated cone perforated at the bottom, a series of radially disposed baffle plates mounted in said pan, a funnel mounted beneath the opening in the center of said cone, a cylinder below said funnel, a worm conveyer mounted in said cylinder, means for vanning said pan, and means for simultaneously rotating said worm conveyer, with means for varying the speed of said worm conveyer, substantially as described.

8. Apparatus for concentrating ores, comprising a pan provided with a peripheral overflow and having a bottom in the form of an inverted truncated cone perforated at the bottom, a series of radially disposed baffle plates mounted in said pan, said baffle plates having elongated slots therethrough adjacent to the bottom of said pan, and said baffle plates being of less depth than the corresponding portion of the pan, a funnel mounted beneath the opening in the center of said cone, a cylinder below said funnel, a worm conveyer mounted in said cylinder, means for vanning said pan, and means for simultaneously rotating said worm conveyer, with means for varying the speed of said worm conveyer, substantially as described.

9. Apparatus for concentrating ores, comprising a pan provided with a peripheral overflow and having a bottom in the form of an inverted truncated cone perforated at the bottom, radial baffle plates symmetrically disposed mounted in said pan, a cylinder mounted beneath the opening in the center of said cone, a worm conveyer mounted in said cylinder, means for vanning said pan, means for simultaneously rotating said worm conveyer, and a feeding device mounted over the center of said pan and comprising a cylindrical receptacle, means for feeding the mixed ore and water to the center of said receptacle, and a circular trough mounted below and exterior to said receptacle and receiving the mixture overflowing from said receptacle and delivering it in a uniform sheet to said pan, substantially as described.

10. Apparatus for concentrating ores, comprising a pan provided with a peripheral overflow and having a bottom in the form of an inverted truncated cone perforated at the bottom, radial baffle plates symmetrically disposed mounted in said pan, and a feeding device mounted over the center of said pan and comprising a cylindrical receptacle, means for feeding the mixed ore and water to the center of said receptacle, and a circular trough mounted below and exterior to said receptacle and receiving the mixture overflowing from said receptacle and delivering it in a uniform sheet to said pan, substantially as described.

11. Apparatus for concentrating ores, comprising a pan provided with a peripheral

overflow and having a bottom in the form of an inverted truncated cone perforated at the bottom, a series of radially disposed baffle plates of varying length symmetrically disposed mounted in said pan, said baffle plates having elongated slots therethrough adjacent to the bottom of said pan, and said baf-

fle plates being of less depth than the corresponding portion of the pan, means for vaning said pan, and means for withdrawing 10 the concentrates from said pan, substantially as described.

In testimony whereof, I affix my signature.

WASHINGTON BAKER VANDERLIP.
